(57) **CLAIM**

The ornamental design for an laser, as shown and described.

DESCRIPTION

FIG. 1 is a front perspective view of an laser showing my new design;

FIG. 2 is a front view thereof;

FIG. 3 is a top view thereof, the bottom, right and left views being mirror images thereof; and,

FIG. 4 is a rear view thereof.

Any broken lines present are indicative of environmental structure in the drawing and are not part of the design sought to be patented.

1 Claim, 2 Drawing Sheets

FIG. 1

FIG. 2

FIG. 4

FIG. 3
